HOOK AND EYE FASTENING

Richard W. Hempel, North Tonawanda, N. Y.

Application July 22, 1937, Serial No. 155,060

5 Claims. (Cl. 292—129)

This invention relates to a fastening which is adapted to detachably connect two relatively movable parts or members such, for example, as a screen door or window sash and a frame on which the door or window sash is pivotally mounted to swing into an open or closed position.

In fastenings usually heretofore employed for this purpose the latch had the form of a hook and the keeper had the form of a screw eye and the hook and eye were arranged in a definite position relatively to each other. This necessitated mounting these fastening elements on the respective parts or members so that upon engaging or coupling the same the door or sash 10 would hold in its properly closed position, otherwise these elements if spaced too close together would cause the door or sash to be left in a more or less open or loose position and if these elements were arranged too far apart then the same 15 could only be operated with difficulty in order to engage these fastening elements with each other.

It is one of the purposes of this invention to provide a fastening of this character which 20 renders it unnecessary to attach the component elements of the same accurately to the relatively movable parts, such as a screen door and frame, which are to be connected and still enable the door or sash to be held in a tightly closed position and thus avoid either a loosely closed door 25 or sash or one which is shut unduly tight.

A further object of this invention is to provide a fastening of this character which is comparatively simple in construction, easily operable and 30 adjustable to meet varying conditions and also one which can be manufactured at comparatively low cost.

In the accompanying drawing:

Fig. 1 is an elevation of a door and frame 35 equipped with one form of my invention and showing the same in a closed position for holding the door shut, the door being shown in section. Fig. 2 is a horizontal section taken on line 2—2, Fig. 1.

Figs. 3 and 4 are vertical transverse sections taken on the correspondingly numbered lines in Fig. 1.

Fig. 5 is a perspective view of the form of keeper which is employed in the construction 50 shown in Figs. 1 and 2.

In the following description similar characters of reference indicate like parts in the several figures of the drawing.

Referring to Figs. 1, 2, and 4, the numeral 55 10 represents the stationary part or member of a

building, and the numeral 11 a movable part or member thereof which are adapted to be detachably connected by this improved fastening, which members may consist respectively of a frame and a screen or other door pivotally mounted on the frame and movable relatively thereto or these members may represent the frame and sash of a window which is hinged on the frame, but obviously this fastening device can be used for a variety of other purposes in which similar 10 conditions exist.

In its general organization this fastening comprises a keeper which in the present case is mounted on the stationary member 10 of the building and a latch mounted on the door 11 and 15 adapted to be connected with and disconnected from the keeper.

Although the keeper embodying this improvement may be variously constructed, that shown in Figs. 1, 2, 4 and 5 is constructed as follows: 20

The numeral 12 represents a coupling eye which is arranged horizontally adjacent to a part of the frame 10 and provided with an inwardly projecting arm 13. This arm is mounted on a base 25 which in the preferred construction has the form of a loop comprising an upper longitudinal bar 14 connected at its rear end by means of a bend or bow 15 with the inner end of the eye arm 13, and a lower horizontal bar 16 connected at its front end by a bow or bend 17 with the front 30 end of the upper bar 14 while its rear end is provided with a lug 18 which is bent toward the corresponding end of the upper bar 14 so as to complete the base into the form of a loop. This keeper is preferably constructed of a single piece 35 of wire, as best shown in Fig. 5 thereby reducing the cost of the same. Various means may be employed for securing this keeper to the stationary member or frame 10 of the building, those shown in the drawing including a clamping plate 40 19 having the form of a clip the ends of which are curved and engage the outer side of the keeper bars 14 and 16, as shown in Fig. 4 and thereby hold the loop of the keeper against vertical displacement. This clamping plate is secured to the frame 10 by means of a screw 20 which passes through this plate and through the space between the bars of the loop-shaped base, as shown 45 in Fig. 4. Upon loosening this screw the grip of 50 the clamping plate 19 on the keeper base will be released thereby permitting the keeper to be adjusted horizontally in order to bring the eye 55 of the keeper into the proper position relative to the latch of the door 11 and after such adjust-

ment the keeper will be held firmly in place by tightening this screw.

In order to prevent the keeper from slipping between the frame 10 and the clamping plate 19 the base of the keeper and the clamping plate 19 may be positively interlocked by providing the co-operating surfaces of the bars of the keeper and the clamping plate respectively with serrations 21, 22, as shown in Figs. 1, 2 and 5.

10 The particular form of latch shown in Figs. 1, 2, 3 and 4 which embodies my invention is constructed as follows:

15 The numeral 23 represents a longitudinal coupling rod or shank which is provided at its front end with a coupling hook 24 adapted to engage with the coupling eye 12 of the keeper. At its rear end this coupling rod is provided with a connecting eye 25, which together with the hook 24, and the rod 23, are preferably constructed of 20 a single piece of wire, as shown in Fig. 1.

25 Adjacent to the rear end of the coupling rod or shank 23 is a coupling yoke which comprises upper and lower longitudinal bars 26, 27 arranged on opposite sides of this rod and its connecting eye 25, a bow or bend 28 connecting the rear ends of these bars and a guide eye 29 arranged at the front end of one of these bars and surrounding the adjacent part of the coupling rod 23. The yoke is pivotally mounted on the adjacent part 30 of the door or sash 11 by passing its rear bow 28 through the eye 30 of a screw 31 secured to the adjacent part of this door. The longitudinal bars 26, 27, the guide eye 29 and the bow 28 of the yoke are preferably constructed from a single 35 piece of wire, as shown in Figs. 1 and 2.

30 The numerals 32 and 33 represent two plates which form part of a clip which embraces the opposite sides of the yoke bars and the connecting eye of the coupling rod 23, these two plates being preferably connected at one end by a web 34 and constructed integrally therewith from a single piece of sheet metal. The plates 32 and 33 are connected with each other and also with the connecting eye 25 by means of a screw 35 passing through this eye and engaging its threaded end with one of these plates while its head engages the other one of these plates, as shown in Fig. 3. The two plates 32, 33 are capable of sliding lengthwise on the longitudinal bars of the yoke and the coupling bar 23 slides in the guide eye 29 of the yoke, thereby enabling the plates 32 and 33 and the hook supporting rod 23 to move lengthwise relative to the yoke but to be held against transverse movement thereon. The hook supporting rod and the parts connected therewith are yieldingly held in a retracted or rearward position relative to the yoke by means of a spring 36 which surrounds the rear part of the hook rod 23 and is interposed between the guide eye 29 of the yoke and the connecting eye 25 of the hook rod, as best shown in Fig. 1.

35 The construction of the parts is such that when the coupling hook 24 is disengaged from the eye 12 of the keeper the resilience of the spring 36 will draw the hook rod backwardly together with the plates 32, 33 and associated parts until either the connecting eye 25 engages with the screw eye 30 which serves as a stop, or until the expansion of this spring has been exhausted. When the 40 hook rod is thus retracted the hook 24 is in a position which is short of permitting the same to freely engage the keeper eye 12 when the door 11 is in its closed position and it therefore becomes necessary to draw the hook rod forwardly a sufficient extent to permit the coupling hook 24 to

be engaged with the keeper eye 12. During withdrawal of this hook and associated parts relative to the yoke the spring 36 is compressed or put under greater tension, whereby a constant pull will be exerted by this hook against the keeper eye when these parts are engaged with each other, thereby holding the door yieldingly in its closed position and preventing the same from rattling. If it is found that the position of the keeper eye on the frame is such that the coupling hook has to be projected too far for convenient engagement of the same with the keeper eye then the latter can be adjusted on the frame in a direction lengthwise of the projecting and retracting movement of the coupling hook as far as may be necessary to permit of coupling and uncoupling these parts easily and conveniently and still hold the door in its properly closed position.

50 It will thus be noted that by means of this improvement it is not absolutely necessary to attach the latch and keeper of the fastening device originally in the exact position that these parts operate most efficiently for holding the door properly in its closed position, but instead the keeper and latch may be attached in their approximately correct positions which they should occupy on the relatively movable members or parts which are to be detachably connected and still permit operation of the fastening to be effected with ease and facility for retaining the door or sash in a properly closed position.

55 In order to provide a wide range of adjustment for the keeper to suit different conditions the same may be provided with an additional coupling eye 121 which is offset horizontally in a forward direction relative to the other eye 12 of the keeper and connected by an arm 161 with the lower bar of the loop 16, as shown by dotted lines in Fig. 5. By means of a keeper having two coupling eyes which are offset horizontally it is 60 possible to engage the hook 24 of the latch with either one of these eyes in order to either hold the door shut tightly or in a slightly open position for ventilation or other purposes.

65 I claim as my invention:

1. A fastening for detachably connecting two relatively movable parts one of which is provided with a keeper having a coupling eye; said fastening comprising a latch including a rod, a coupling hook arranged on the front end of said rod and adapted to engage said eye, a yoke having two longitudinal bars arranged on opposite sides of said rod, a bow connecting the rear ends of said bars and connected with the other of said relatively movable parts, a loop arranged on the front end of one of said bars and surrounding said rod, plates arranged on opposite sides of said rod and bars, and a screw connecting said plates and rod.

2. A fastening for detachably connecting two relatively movable parts one of which is provided with a keeper having a coupling eye; said fastening comprising a latch including a rod, a coupling hook arranged on the front end of said rod and adapted to engage said eye and provided at its rear end with a connecting eye, a yoke having two longitudinal bars arranged on opposite sides of said rod, a loop arranged on the front end of one of said bars and surrounding said rod and a bow connecting the rear ends of said bars and pivotally mounted on the other of said relatively movable parts, plates arranged on opposite sides of said bars and said connecting eye, and a bolt connecting said plates and passing through said connecting eye.

3. A fastening for detachably connecting two relatively movable parts one of which is provided with a keeper having a coupling eye; said fastening comprising a latch including a rod, a coupling hook arranged on the front end of said rod and adapted to engage said eye and provided at its rear end with a connecting eye, a yoke having two longitudinal bars arranged on opposite sides of said rod, a loop arranged on the front end of one of said bars and surrounding said rod and a bow connecting the rear ends of said bars and pivotally mounted on the other of said relatively movable parts, plates arranged on opposite sides of said bars and said connecting eye, a bolt connecting said plates and passing through said connecting eye, and a spring surrounding said rod and interposed between said loop and said connecting eye.
4. A fastening for detachably connecting two relatively movable parts one of which is provided with a keeper having a coupling eye; said fastening comprising a latch including a rod, a coupling hook arranged on the front end of said rod and adapted to engage said eye and provided at its rear end with a connecting eye, a yoke having two longitudinal bars arranged on opposite sides of said rod, a loop arranged on the front end of one of said bars and surrounding said rod and a bow connecting the rear ends of said bars and pivotally mounted on the other of said relatively movable parts, plates arranged on opposite sides of said bars and said connecting eye, a bolt connecting said plates and passing through said connecting eye, a web connecting corresponding ends of said plates, and a spring surrounding said rod and interposed between said connecting eye and said loop.

said rod and a bow connecting the rear ends of said bars and pivotally mounted on the other of said relatively movable parts, plates arranged on opposite sides of said bars and said connecting eye, a bolt connecting said plates and passing through said connecting eye, and a web connecting corresponding ends of said plates. 5

5. A fastening for detachably connecting two relatively movable parts one of which is provided with a keeper having a coupling eye; said fastening comprising a latch including a rod, a coupling hook arranged on the front end of said rod and adapted to engage said eye and provided at its rear end with a connecting eye, a yoke having two longitudinal bars arranged on opposite sides of said rod, a loop arranged on the front end of one of said bars and surrounding said rod and a bow connecting the rear ends of said bars and pivotally mounted on the other of said relatively movable parts, plates arranged on opposite sides of said bars and said connecting eye, a bolt connecting said plates and passing through said connecting eye, a web connecting corresponding ends of said plates, and a spring surrounding said rod and interposed between said connecting eye 20 25 and said loop. 25
